UNITED STATES PATENT OFFICE.

ROY H. BROWNLEE, OF PITTSBURGH, PENNSYLVANIA.

DENTIFRICE.

No Drawing.

Application filed October 13, 1926. Serial No. 141,426.

This invention relates to a dentifrice, and the present application constitutes a continuation in part of application Serial No. 82,851, filed January 21, 1926.

5 The object of the invention is to provide a dentifrice which has no injurious effect upon the tissues or glands of the mouth, and which possesses certain particularly advantageous properties for cleansing the teeth 10 and gums and for the general care of the oral cavity.

A problem encountered in compound a satisfactory dentifrice is to provide a substance which thoroughly cleanses the teeth; 15 but which contains no gritty substance capable of wearing away the enamel of the teeth, and no ingredient capable of exerting a solvent action thereon.

A corollary function of a complete dentifrice is to dissolve and completely remove 20 oils, fats, and mucin from the teeth; thus preventing the formation of tartar and other deposits, and exposing the actual surface of the teeth to direct contact of the cleansing 25 instrument to secure a thorough cleansing thereof.

A still further desirable property of a dentifrice is to be capable of exerting a mild 30 antiseptic action, thus retarding the increase of bacteria within the oral cavity without injuring any tissues of the mouth or gums.

The dentifrice of the present invention meets these requirements by the incorporation 35 therein of a substance which acts as a solvent of fats, oils, and mucin; and which has a mild antiseptic effect, without injuring the teeth or tissues or impairing the flow or alkalinity of the saliva.

One substance having these desirable 40 properties for use in a dentifrice is the polyhalide of methane, carbon tetrachloride or tetrachlor methane (CCl_4).

Another substance having unusually desirable properties is ethyl iodide (C_2H_5I), 45 which is the iodine substitution product of ethane.

While either of these substances alone is highly satisfactory as the sole active ingredient of a dentifrice, in combination they 50 present an almost ideal active principle for the purpose. This is because the carbon tetrachloride exerts a somewhat greater solvent and cleansing effect than the ethyl iodide, while the ethyl iodide has somewhat 55 higher antiseptic properties than the carbon

tetrachloride. Both these organic halides exert no injurious effect on the teeth or tissues.

As used in a dental cream, these active ingredients are combined with relatively inert 60 substances which provide filling, carrying, and polishing material.

The following formula, is one which has been found to give satisfactory results:

	Grams.
Calcium carbonate (prepared chalk)	100
Magnesium carbonate	50
Tetra-chlor-methane	20-30
Ethyl-iodide	3-10
White mineral oil (highly refined petroleum oil of the lubricating grade)	70
Oil of anise	40-50
Eucalyptol	5
Menthol	2-3
Sodium chloride	1
Soap	75
Glycerine	2-3
Water	10
	145
	145
	80

It should be understood that the formula given above is illustrative only, and that the ingredients other than the carbon tetrachloride and ethyl iodide may be varied in order to provide a dental cream of any desired 35 consistency and flavor. The amount of carbon tetrachloride and ethyl iodide may also be varied, and as these substances are harmless, they may be included in as great a combined amount as will remain in a uniform 40 mechanical mixture with the other ingredients of the composition. There is also no definite lower limit to the amount of these substances which may be used, as any appreciable quantity will exert a beneficial 45 effect. In order that the most advantageous results may be obtained, however, it is desirable that the combined amount of carbon tetrachloride and ethyl iodide in the composition should be from one-twentieth 50 of the total weight of the composition to an amount as great as may be retained in satisfactory condition therein.

Certain other organic halides may be incorporated in the dentrifrice to replace the 55 carbon tetrachloride or ethyl iodide. Of the other halides of methane, di-iodo methane may be used in the composition if desired. On the trihalides of methane, chloroform may be used, although its high rate of evap- 60

oration and lower cleaning properties render it a less desirable ingredient than the carbon tetrachloride. It should be understood that in this connection the chloroform is included for its solvent and cleansing properties. Its antiseptic action is only of secondary importance, while its anesthetic properties are wholly foreign to the purposes of the dentifrice. Carbon tetra iodide possesses physical and chemical properties which render its use possible and desirable.

Of the halides of the higher members of the paraffin series various substances may be advantageously utilized. Not only the monohalides of the paraffin series, but also the di-halides and poly-halides of the series may be employed when their physical properties render them suitable for use in a dentifrice.

In regard to any of these substances, it may be stated as a general principle that the more desirable are those having a boiling point between twenty-five degrees centigrade and one hundred and fifty degrees centigrade. To express the matter differently, the more desirable are those which are liquids at room temperature and atmospheric pressure. The compounds having a boiling point lower than twenty-five degrees centigrade tend to evaporate from or separate in the composition, while those which are solid at room temperature and atmospheric pressure are too inactive to impart the desired qualities to the dentifrice.

The halogen substitution products of several of the ethylene series of hydrocarbons may also be used instead of carbon tetrachloride in a dentifrice. Of these the most suitable member is ethylene chloride ($C_2H_4Cl_2$). A number of the halides of the acetylene series also possess suitable characteristics.

It should be understood that a number of the halides of both the saturated and unsaturated series, which have physical properties rendering them suitable, are relatively so rare that their use in a dentifrice is rendered commercially impractical.

It should also be understood that odor, or taste, as well as boiling point, is of importance in considering the desirability of any compound from the view point of its physical properties. Thus many of the bromides have such a penetrating and disagreeable odor that their use is in effect precluded by the impossibility of using flavoring matter which will cover or neutralize the same.

A very desirable mixture is that of ethylene chloride together with either or both carbon tetrachloride and ethyl iodide. This is for the reason that ethylene chloride has a particularly sweet taste and pleasant odor, so that in itself it serves as a flavoring ingredient as well as exercising a solvent and antiseptic effect. When the ethylene chloride is used the mixture of active ingredi-

ents may desirably consist in ten to twenty (10 to 20%) per cent of the ethylene chloride, and the remainder of either or both carbon tetrachloride and ethyl iodide.

In addition to the dental cream, one or more halogen substitution products of hydrocarbons may be used in liquid form to secure an occasional thorough cleansing of the teeth. One such liquid may consist merely of a mixture of tetrachlor methane and ethyl iodide. To such mixture white mineral oil may be added, if so desired, to retard evaporation of these volatile liquids. A satisfactory formula for such liquid may be given as follows:

	Grams.
Tetrachlor methane	6
Ethyl iodide	1
White mineral oil	4

While white mineral oil is highly desirable because of its lack of taste and odor, various other mineral, animal, or vegetable oils may be substituted for it. For example, highly refined olive oil or cottonseed oil may be employed.

What I claim is:

1. A dentifrice comprising as its principal active ingredients a chloride of an aliphatic hydrocarbon, and ethyl iodide.
2. A dentifrice comprising as its principal active ingredients carbon tetrachloride, and an iodide of an aliphatic hydrocarbon.
3. A dental cream comprising as its principal active ingredients a chloride of an aliphatic hydrocarbon and ethyl iodide; filling material, and a white mineral oil.
4. A dental cream comprising as its principal active ingredients carbon tetrachloride and an iodide of an aliphatic hydrocarbon; filling material, and a white mineral oil.
5. A dentifrice comprising a chloride of an aliphatic hydrocarbon and an iodide of an aliphatic hydrocarbon, each of such halides having its boiling point between the limits of twenty-five degrees centigrade and one hundred fifty degrees centigrade, the halides being present in a combined amount constituting no less than one-twentieth by weight of the total composition.
6. A dentifrice comprising at least two different halides of aliphatic hydrocarbons, each of such halides having its boiling point between the limits of twenty-five degrees centigrade and one hundred fifty degrees centigrade, the halides being present in a combined amount constituting no less than one-twentieth by weight of the total composition.
7. A dental cream comprising a chloride of an aliphatic hydrocarbon and an iodide of an aliphatic hydrocarbon, each of such halides having its boiling point between the limits of twenty-five degrees centigrade and one hundred fifty degrees centigrade, the halides being present in a combined amount

no less than one-twentieth by weight of the total composition, filling material, and a white mineral oil.

8. A dental cream comprising two different halides of aliphatic hydrocarbons, each of such halides having its boiling point between the limits of twenty-five degrees centigrade and one hundred fifty degrees centigrade, the halides being present in a combined amount no less than one-twentieth by weight of the total composition, filling material, and a white mineral oil.

9. A dentifrice comprising carbon tetrachloride and ethyl iodide as its principal active ingredients.

10. A dental cream comprising carbon

tetrachloride, ethyl iodide, filling material, and a white mineral oil.

11. A dental preparation comprising carbon tetrachloride and ethyl iodide, both in liquid form.

12. A dental preparation comprising carbon tetrachloride and ethyl iodide, both in liquid form, and a white mineral oil.

13. A dental preparation comprising carbon tetrachloride and ethyl iodide, both in liquid form, and an oleaginous carrier for the halides.

In witness whereof, I hereunto set my hand.

ROY H. BROWNLEE.
